FUSE FOR PROJECTILES

Hermann H. Zornig, Newhall, Iowa

Application May 6, 1933, Serial No. 669,665

15 Claims. (Cl. 102—39)

(Granted under the act of March 3, 1883, as
amended April 30, 1928, 370 O. G. 757)

The invention described herein may be manufactured and used by or for the Government for governmental purposes, without the payment to me of any royalty thereon.

The subject of this invention is a fuse for projectiles.

The principal object of the invention is to provide a novel arming device whose movement to released position is initiated on set-back and completed through the action of centrifugal force due to the rotation of the projectile while the force of setback is still operative.

Accordingly a fuse may be made which can be armed at the very low setback forces and rotation developed with the small propelling charges in howitzers and mortars and still be safe in handling and transportation because of the practical impossibilities of obtaining under these conditions the application of the forces of setback and rotation in the sequence required to move the mechanism into the armed position.

Another object is to arrange the arming device as a self-contained unit so that it may be readily assembled to a fuse.

With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawing, wherein:

Fig. 1 is a longitudinal sectional view of a fuse showing the arming device unit in side elevation.

Figs. 2, 3, 4 and 5 are views in longitudinal section showing various positions assumed by the arming device.

Referring to Fig. 1 there is shown a fuse body comprising a base 5 having a reduced rear portion 6 adapted to be threaded attached to a projectile and a reduced front portion 7 adapted to threadedly mount a fuse head 8 carrying a striker 9 in its nose. The base 5 and 8 are formed with recesses or chambers, respectively 10 and 11, which are in communication and receive the firing mechanism unit shown in Figs. 2 to 5.

Referring to Fig. 2 the unit comprises a casing having a cylindrical body wall 12 and a reduced cylindrical neck 13 joined by an offset including an inclined portion 14 and a flat portion 15 whose functions will appear hereinafter. The casing includes a bottom 16 having a central, inturned,

tubular flange 17. A tube 18 is inserted through the flange 17 with its inner portion substantially coextensive with the body 12 of the casing and its outer projecting portion adapted to fit in the recess 10 of the base 5 which aids in holding it in the assembled position. The outer portion of the tube carries a primer 19 adapted to be set off by a firing pin whose stem 20 passes through the inner portion of the tube and through an aperture 21 in a diaphragm 22.

A spring 23 seated on the diaphragm acts on a guide collar 24 on the firing pin and normally holds the point of the firing pin away from the primer. A head 25 on the firing pin, of substantially the same external diameter as the tube 18, is held against the floor 26 of the head 8 and in position to be engaged by the striker 9 through the action of the spring 23. A plurality of blocks 27—27 embrace the stem of the firing pin and are interposed between the head 25 and the rim of the tube 18. The blocks serve, until they are removed, to positively prevent actuation of the firing pin.

Referring to Fig. 3 the blocks 27 are normally held against removal by means of a sleeve 28 slidably mounted on the end of the tube 18. The sleeve is formed with a collar 29 fitting within the neck 13 and in the normal unarmed condition of the mechanism, as shown in Fig. 2, forming a closure for the container.

Mounted within the cylindrical wall 12 of the casing is an annular, cup-shaped plunger 30 embracing the flange 17 and the sleeve 28. The plunger is normally held in a forward position against lugs 31 by means of a coil spring 32 embracing the lower portion of the plunger and confined between the bottom 16 of the casing and an offset 33 of the plunger. The lugs 31 hold a ring 34 against the flat portion 15 of the casing offset. The ring has an internal diameter corresponding to that of the neck 13 and consequently cooperates with the inclined portion 14 of the casing offset to form an annular recess 35.

The sleeve 28 and the plunger 30 are connected by a plurality of sets of toggle links 36 and 37, preferably of unequal length and connected by a pivot pin 38. The shorter links 36 are pivotally mounted in a slotted ring 39 secured to the sleeve and the longer links 37 are mounted in a slotted ring 40 secured in the plunger.

The links 36 are all mounted on a common wire 41 fitting in an annular groove 42 in the ring 39. The links 37 are similarly mounted on a common wire 37a.

The pivot 38 of the shorter link is closer to the

110

axis of the firing mechanism unit than the pivot 42 of the longer link. The knee of the toggle is normally disposed towards the axle of the unit and is maintained in this direction through the tension of the plunger spring 32. Bending of the toggle in this direction is limited by engagement of the end of the long link 37 with the sleeve 28. The link 37 is formed with an offset 43 (Fig. 4) and the pin 38 engages the end of the offset remote from the pivot 42. The short link 36 is formed to provide on its outer side a hook 44 adapted to enter the recess 35 (Fig. 5).

The normal position of the parts is as shown in Fig. 2 with the sleeve 28 held in position to prevent removal of the blocks 27, the toggle links breaking joint inwardly.

When a projectile equipped with the fuse is subjected to the forces of set-back, as occurs when it is fired from a gun, the parts assume the position shown in Fig. 3. The plunger 30 has moved rearwardly as far as possible and the sleeve 28 by virtue of its connection therewith through the toggle links has also been moved rearwardly a corresponding amount. This initial movement of the sleeve is only sufficient to partially uncover the blocks 27. If set-back is not followed by rotation of the projectile the plunger spring will act through the links to restore the sleeve 28 to its normal position shown in Fig. 2.

When the projectile is fired from the gun it is rotated in the accepted manner. Under the influence of centrifugal force the knee of the toggle links moves radially and the parts assume the relation shown in Fig. 4, with the long links 37 in a position parallel to the axis of the unit and the short links moving to a position substantially perpendicular to the axis of the unit. The sleeve 28 connected to the short links is moved clear of the blocks 27 which under the influence of centrifugal force move radially to the positions indicated, and free the firing pin. When the plunger recovers from the influence of the force of set-back it can be moved forward by its spring only a short distance inasmuch as the extremities of the long links 37 will engage the ring 34.

Referring now to Fig. 5, there is shown the position of the parts when the projectile is subjected to rotation followed by set-back, which sequence may occur during handling and transportation. Under these conditions the outward movement of the knees of the toggles as resulting from centrifugal force will cause the hooks 44 of the short links 36 to enter the annular recess 35 and prevent the sleeve 28 from moving rearwardly a sufficient distance to uncover the blocks 27. When the projectile is in a state of rest after such an action the plunger spring is effective to restore the parts to the normal position of Fig. 2.

When the firing pin has been released to armed position (Fig. 4) it is held away from the primer by its spring 23 until driven rearwardly by the striker 9 on impact, or the retardation of the projectile causes the tube 18 to move forward due to its own momentum in case the projectile strikes the target in such a manner that the striker 9 is not driven back.

I claim.

1. A firing mechanism for a fuse embodying a container, a bottom for the container having a central inturned flange, a tube secured to the flange and extending into the container, a primer in the bottom end of the tube, a firing pin in the upper end of the tube, a head on the firing pin,

centrifugally releasable blocks between the firing pin head and the tube, a sleeve slidable on the tube and adapted to confine the releasable blocks, a plunger within the container, a spring normally holding the plunger in a forward position and sets of jointed links connecting the plunger and the sleeve and having first a longitudinal movement and then a radial movement with the sleeve and plunger in breaking joint whereby the sleeve is moved relative to the plunger and from its normal position confining the blocks.

2. A firing mechanism for a fuse embodying a container, a bottom for the container having a central inturned flange, a tube secured to the flange and extending into the container, a primer in the bottom end of the tube, a firing pin in the upper end of the tube, a head on the firing pin, centrifugally releasable blocks between the firing pin head and the tube, a sleeve slidable on the tube and adapted to confine the releasable blocks, a plunger within the container, a spring normally holding the plunger in a forward position and means connecting the plunger and sleeve for normally holding the sleeve in position to confine the blocks and operable during flight to move the sleeve from block-confining position.

3. A firing mechanism for a fuse embodying a container, a tube axially of the container, a firing pin in the upper end of the tube, a head on the firing pin, centrifugally releasable blocks between the firing pin head and the tube, a sleeve slidable on the tube and adapted to confine the releasable blocks, a plunger within the container, a spring normally holding the plunger in a forward position and means connecting the plunger and sleeve for normally holding the sleeve in position to confine the blocks and operable during flight to move the sleeve from block-confining position.

4. In a fuse, a container, a tube within the container, an element of a firing mechanism extending into the tube, a sleeve for controlling release of said element and movable on the tube, a plunger movable relative to the tube, a spring for normally holding the plunger in a forward position, sets of toggle links connecting the sleeve and plunger and normally breaking joint inwardly, each set consisting of a short link pivoted on the sleeve and a long link having an offset pivoted on the plunger, the pivot of the short link being closer to the axis of the tube than the pivot of the long link, a knee pivot between the links engaging the end of the offset of the long link remote from the pivot thereof, and a hook on the short link adapted to engage the container when the links break joint outwardly before setting back whereby the sleeve is retained against movement to releasing position.

5. In a fuse, a container, a tube within the container, an element of a firing mechanism extending into the tube, a sleeve for controlling release of said element and movable on the tube, a plunger movable relative to the tube, a spring for normally holding the plunger in a forward position, sets of toggle links connecting the sleeve and plunger and normally breaking joint inwardly, each set consisting of a short link pivoted on the sleeve and a long link having an offset pivoted on the plunger, the pivot of the short link being closer to the axis of the tube than the pivot of the long link, a knee pivot between the links engaging the end of the offset of the long link remote from the pivot thereof.

6. In a fuse, a container, a tube within the container, an element of a firing mechanism extending

- ing into the tube, a sleeve for controlling release of said element and movable on the tube, a plunger movable relative to the tube, a spring for normally holding the plunger in a forward position, sets of toggle links connecting the sleeve and plunger and normally breaking joint inwardly, each set consisting of a short link pivoted on the sleeve and a long link pivoted on the plunger, the pivot of the short link being closer to the axis of the tube than the pivot of the long link. 5
7. In a fuse, an element of a firing mechanism, a member mounted for longitudinal movement and controlling release of said element, a plunger mounted for longitudinal movement, a spring normally holding the plunger in a forward position, toggle links connecting the member and plunger, said links normally breaking joint inwardly and adapted when in set-back position to break joint outwardly under the action of centrifugal force whereby to effect movement of the member to releasing position. 15
8. In a fuse, an element of a firing mechanism, a member mounted for longitudinal movement and controlling release of said element, a plunger mounted for longitudinal movement, a spring normally holding the plunger in a forward position, toggle links connecting the member and plunger, said links under the action of the plunger spring normally holding the releasing member at a spaced distance from the plunger and operable under the action of centrifugal force to draw the releasing member towards the plunger to release the element of the firing mechanism. 25
9. In a fuse, an element of a firing mechanism, a member mounted for longitudinal movement and controlling release of said element, a plunger mounted for longitudinal movement, a spring normally holding the plunger in a forward position, toggle links connecting the member and plunger and means for limiting outward movement of the knee joint of the links except when the links are in set-back position whereby the releasing member is maintained in non-releasing position. 35
10. In a fuse, a pair of members mounted for longitudinal movement, jointed links pivotally attached to both of the members and operable upon the sequence of forces of set-back and rotation of the fuse to move the members towards one another. 40
11. In a fuse, a pair of members mounted for longitudinal movement, jointed links pivotally attached to both of the members and operable upon rotation of the fuse to move the members towards one another. 80
12. In a fuse, a pair of members mounted for longitudinal movement, jointed links pivotally attached to both of the members and having first a longitudinal movement with said members and then a radial movement in breaking joint to move the members towards one another. 85
13. In a fuse, a container having a main portion and an offset providing a reduced portion, a pair of members mounted for longitudinal movement, one of said members being within the main portion of the container and the other being normally within the reduced portion, links connecting the members and operable on set-back and centrifugal force to move the member in the reduced portion into the main portion of the container, and means on one of the links movable into engagement with the offset to restrain movement of the member from the reduced portion when the links are subjected to centrifugal force without set-back. 90
14. In a fuse, a container having a main portion and a reduced portion, a pair of members mounted for longitudinal movement, one of said members being within the main portion of the container and the other being normally within the reduced portion, links connecting the members and operable on set-back and centrifugal force to move the member in the reduced portion into the main portion of the container. 100
15. In a fuse, a base, a head on the base, a striker in the head, a container housed in the fuse between the base and head, an element or a firing mechanism mounted for movement in the container, and means within the container for controlling release of said element and including links operable upon the sequence of the forces of set-back and rotation. 115
